LOCOMOTIVE FIREBOX EQUIPMENT

Chester A. Siegel, Newark, N. J., assignor to
 American Arch Company, New York, N. Y., a
 corporation of Delaware

Application February 23, 1942, Serial No. 431,978

8 Claims. (Cl. 122—68)

This invention relates to locomotive firebox equipment, and is particularly concerned with improved water steaming and circulating devices adapted to be installed in locomotive fireboxes.

The provision of circulator devices in locomotive fireboxes is desirable to promote boiler circulation and heat absorption, and with this general object in view the invention provides for the employment of a circulator device incorporating a transverse flattened body having appreciable surface area, said body being of novel construction and its extended surface area being located in the firebox in a novel manner, as will further appear.

In addition to providing increased heat absorption area, the circulator with the flattened body is further arranged to effectively cooperate with other circulator devices in supporting a fire brick arch. More specifically, the construction and arrangement is such that uniform brick patterns may be used throughout the brick arch, notwithstanding differences of shape as between several circulator devices employed in a given installation.

The circulator with the flattened body contemplated by this invention is desirably located toward the forward end of the firebox, and is so arranged that at least a large part of its surface area projects downwardly below the average plane of the fire brick arch, said area lying approximately in an upright plane extended transversely of the firebox. In this way, if desired, the plane of the arch may be raised somewhat, at least in a forward region thereof, without resulting in short circuiting of the fuel and flame stream at the forward edge of the arch. By raising the arch, increased clearance for firing is afforded.

For certain purposes, in some locomotives, a combustion chamber is desirably located just to the rear of the boiler flue sheet and above and forwardly of the fire brick arch. Some locomotives are initially constructed with such a combustion chamber formed in the boiler shell ahead of the throat of the firebox. In locomotives not having that type of combustion chamber, the improved circulator of the present invention having a flattened transverse body may be arranged to provide a combustion chamber of the type referred to. For this purpose, the flattened body circulator of this invention may be located with its lower edge close to the firebox grates, at an appropriate distance to the rear of the throat sheet, thereby separating a forward portion of the firebox space, to form a combustion chamber.

The foregoing and other advantages of the invention may be secured by a construction of the

type shown in the accompanying drawing, illustrating two embodiments. In the drawing—

Figure 1 is a longitudinal vertical sectional view through a locomotive firebox equipped with circulator devices in accordance with the present invention;

Fig. 2 is a transverse sectional view taken substantially as indicated by the line 2—2 on Figure 1; and

Figure 3 is a view similar to Figure 1 but illustrating a modified installation.

From Figures 1 and 2 it will be seen that the firebox is defined by side sheets 4—4, a crown sheet 5, a throat sheet 6 and a back sheet 7. 15 These several sheets cooperate with spaced outer sheets to form water legs surrounding the firebox. Thus a wrapper sheet 8 surrounds the top and sides of the firebox, an outside throat sheet 9 and back sheet 10 cooperating, respectively, with the 20 inside sheets 6 and 7 at the throat and back. The boiler shell 11 projects forwardly from the outside sheets, a multiplicity of flue tubes 12 (only two being shown) being extended forwardly through the boiler barrel in accordance with known practice. 25 The flue tubes 12 cooperate with flue sheet 13 which defines the forward end of the firebox proper.

The water legs surrounding the firebox are closed by a mud ring 14 in the general plane of 30 which the fuel grates (not shown) are ordinarily located. A fire door appears in the backhead at 15.

A series of circulator devices is arranged within 35 the firebox, each of these devices comprising a transverse inlet portion 16 having its ends connected with the water space through the side sheets 4—4. Each circulator further incorporates an outlet portion 17 connected with the inlet portion toward the center of the box and extended 40 upwardly therefrom for communication with the boiler space through the crown sheet 5. The inlet portions 16 of the several circulators are preferably arched, as clearly appears in Figure 2, and the several inlet portions are arranged in parallelism approximately in a common plane, so as 45 to support arch brick 18.

The forwardmost circulator is similar in general arrangement to the remaining circulators, but this circulator incorporates a relatively large flattened body 16a constituting the inlet portion thereof. From the drawing it will be seen that this flattened body extends transversely of the firebox in a generally upright plane, the ends being connected with the boiler space through

the side sheets, and the body preferably being staybolted, as shown in Figure 2. From Figure 2 it is also seen that the body 16a presents appreciably extended surface area for heat absorption, this area depending below the mean plane of the arch formed by bricks 18.

It is also to be observed that the upper edge of the flattened body 16a (see Figure 2) is inclined upwardly and inwardly from each side sheet, the outlet 17 being coupled therewith at the high point, so as to provide effective circulation through this device and avoid regions of sluggish circulation. Note further that the upper edge of the body 16a is located generally in the same plane as the inlet portions 16 of the remaining circulators. In this way, uniform brick patterns may be employed throughout the fire arch.

By arrangement of the forward circulator as shown in Figures 1 and 2, with the lower edge of the body 16a close to the grate line g, the flattened body 16a serves, in effect, as a transverse partition dividing the forward part of the firebox from the rearward portion thereof. Thus, in a locomotive of the type shown in Figures 1 and 2, a combustion chamber is provided just to the rear of the flue sheet 13, to which combustion chamber air for secondary combustion of the fuel and flame stream may be introduced through the grates just to the rear of the throat sheet.

In the modified arrangement of Figure 3, the locomotive is provided with a combustion chamber 19 within the barrel part of the boiler, and in this installation the flattened body 16b of the forwardmost circulator is positioned at an appreciable height above the grate, the space between this body and the throat sheet being closed by fire brick 20, in order to prevent short circuiting of the fuel and flame stream.

In the arrangement of Figure 3, notwithstanding the fact that a body of appreciable side face area projects downwardly from the plane of the arch formed by bricks 18, the necessary clear space for firing above the grate is not impaired. In fact, as here seen, the arch formed by bricks 18 is located relatively high in the firebox, thereby increasing the clearance over the grate.

In Figure 3, as well as in Figures 1 and 2, the arch may be formed by employment of bricks of uniform pattern substantially throughout, this being accomplished in spite of the fact that various of the circulators differ appreciably from each other in configuration.

Use of uniform brick shapes in both arrangements is facilitated by virtue of the positioning of the flattened inlet body of the forward circulator in a plane approximately at right angles to the mean plane of the arch. It is noted, however, that notwithstanding said positioning of the flattened inlet body, the tubular outlet of that circulator meets the crown sheet at right angles, this being accomplished by employment of a bend in the outlet tube, which also accommodates thermal distortions.

I claim:

1. For a locomotive firebox, a metallic water-circulating and steaming member comprising a transverse flat body adapted to lie in a generally upright plane, open at the ends for connection into the side water legs, and having its upper edge upwardly crowned toward the center, and an outlet extending upwardly from said center and bent to accommodate thermal distortions.

2. For a locomotive firebox, a metallic water-circulating and steaming member comprising a

transverse flat body adapted to lie in a generally upright plane, open at the ends for connection into the side water legs, and having its upper edge upwardly crowned toward the center, and a substantially tubular outlet extending upwardly from said center and bent in the longitudinal plane to accommodate thermal distortions and to facilitate connection to the crown sheet.

3. In a locomotive firebox having an arch 10 which slopes relative to the crown sheet, a metallic water-circulating and steaming member comprising a transverse flat body lying in a plane approximately at right angles to the general plane of the arch, having its ends connected into the side water legs and its upper edge upwardly crowned toward the center, and a substantially tubular outlet extending upwardly from said center and bent in the longitudinal plane to accommodate thermal distortions and to facilitate connection to the crown sheet.

4. In a locomotive firebox, a plurality of water

steaming and circulating devices, each having an inlet portion extending transversely of the firebox, with its ends connected with the side water

legs of the firebox, and each device further having an outlet portion extending upwardly from the inlet portion and connected with the water space above the crown sheet, the inlet portion of one of said circulator devices being enlarged

30 as compared with the inlet portion of other circulator devices and comprising a flattened body of substantial side face area, the body lying in a generally upright plane, and the upper edge of said body and the inlet portions of other circulator devices being located generally parallel to each other in a series, so as to serve for support of fire arch brick lying generally in a common plane, the said flattened circulator being located toward the forward end of the series of circulators, with a substantial portion of the side face area of its body extending below the general plane of the arch, together with additional fire brick between the throat of the firebox and the lower portion of said flattened body.

45 5. In a locomotive firebox, a plurality of water steaming and circulating devices arranged in a series, one in front of another lengthwise of the firebox, each circulator device having an inlet portion extending transversely of the firebox,

50 with its ends connected with the side water legs of the firebox, and each device further having an outlet portion extending upwardly from the inlet portion and connected with the water space above the crown sheet, a fire brick arch sup-

55 ported by said circulator devices, the inlet portion of the circulating device at the forward end of the firebox comprising a flattened body of substantial side face area, lying in a generally upright plane with the upper edge thereof being

60 located in the same general plane as the inlet portions of the other circulator devices and the lower edge thereof lying substantially below the inlet portion of the other circulator devices and serving as a transverse partition dividing the

65 forward part of the firebox from the rearward portion thereof.

6. In a locomotive firebox, a plurality of water

steaming and circulating devices arranged in a series, one in front of another lengthwise of

70 the firebox, each circulator device having an inlet portion extending transversely of the firebox, with its ends connected with the side water legs of the firebox, and each device further having an outlet portion extending upwardly from the

75 inlet portion and connected with the water space

above the crown sheet, the inlet portion of the circulating device at the forward end of the firebox comprising a flattened body of substantial side face area lying in a generally upright plane with the upper edge thereof being located in the same general plane as the inlet portions of the other circulator devices and the lower edge thereof lying below the inlet portions of the other circulator devices and near the plane of the grate, and a fire brick arch supported by said circulator devices.

7. In a locomotive firebox, a plurality of water steaming and circulating devices arranged in a series, one in front of another lengthwise of the firebox, each circulator device having an inlet portion extending transversely of the firebox, with its ends connected with the side water legs of the firebox, and each device further having an outlet portion extending upwardly from the inlet portion and connected with the water space above the crown sheet, the inlet portion of the circulating device at the forward end of the firebox comprising a flattened body of substantial side face area lying in a generally upright plane with the upper edge thereof being located in the same general plane as the inlet portions of the other circulator devices and the lower edge thereof lying below the inlet portions of the

other circulator devices and near the plane of the grate, and spaced rearwardly from the throat sheet, and a fire brick arch supported by said circulator devices.

- 5 8. In a locomotive firebox, a plurality of water steaming and circulating devices arranged in a series, one in front of another lengthwise of the firebox, each circulator device having an inlet portion extending transversely of the firebox,
- 10 15 with its ends connected with the side water legs of the firebox, and each device further having an outlet portion extending upwardly from the inlet portion and connected with the water space above the crown sheet, the inlet portion of the circulator device at the forward end of the firebox comprising a flattened body of substantial side face area lying in a generally upright plane and spaced rearwardly from the flue sheet and throat sheet with the upper edge thereof being
- 20 25 located in the same general plane as the inlet portions of the other circulator devices and the lower edge portion thereof lying below the inlet portion of the other circulator devices and near the plane of the grate, and a fire brick arch supported by said circulator devices, the space between said circulator and the flue and the throat sheet forming a secondary combustion chamber
